(57) **CLAIM**

(21) Appl. No.: **29/340,454**

The ornamental design for a nose hair trimmer with dual cutting edges, as shown and described.

(22) Filed: **Jul. 20, 2009**

DESCRIPTION

(51) **LOC (9) Cl.** **28-03**

FIG. 1 is a front elevational view of a nose hair trimmer with dual cutting edges showing my new design;

(52) **U.S. Cl.** **D28/54**

FIG. 2 is a left side view thereof;

(58) **Field of Classification Search** 30/29.5,

FIG. 3 is a right side view thereof;

30/30, 32, 34.05, 34.1, 34.2, 43–43.92, 44–45,

FIG. 4 is a top plan view thereof;

30/526–537, 196, 201, 223, 233, 233.5; D28/44,

FIG. 5 is a perspective view thereof with an area shown in dashed lines; and,

D28/44.1, 49–54

FIG. 6 is an enlarged view of the area shown in dashed lines in FIG. 5.

See application file for complete search history.

(56) **References Cited**

The broken line showing of the remainder of the nose hair trimmer with dual cutting edges is included for the purpose of illustrating unclaimed portions of the article and forms no part of the claimed design.
